(57) **CLAIM**

The ornamental design for a rod holder, as shown and described.

DESCRIPTION

FIG. 1 is a front perspective view of the rod holder showing my new design.

FIG. 2 is a left side elevation view thereof.

FIG. 3 is a left side elevation view of a second embodiment of FIG. 1.

FIG. 4 is a right side elevation view of the hooking member of the first and second embodiment shown separately for ease of illustration.

FIG. 5 is a top plan view thereof.

FIG. 6 is a front elevation view thereof.

FIG. 7 is a bottom plan view thereof.

FIG. 8 is a cross-sectional view thereof along line 8-8 indicated in FIG. 7.

FIG. 9 is a top plan view of the base of the rod holder of the first and second embodiment shown separately for ease of illustration.

FIG. 10 is a cross-sectional view of FIG. 9 of the first embodiment along line 10, 11 indicated in FIG. 9.

FIG. 11 is a cross-sectional view of FIG. 9 of the second embodiment along line 10, 11 indicated in FIG. 9.

FIG. 12 is a right side elevation view of the base of the rod holder of the first and second embodiment shown separately for ease of illustration.

FIG. 13 is a front elevation view thereof.

FIG. 14 is a bottom plan view of first embodiment of FIG. 9; and,

FIG. 15 is a bottom plan view of second embodiment of FIG. 9.

The broken line showing of parts of the drawings is included for the purpose of illustrating use and environment and forms no part of the claimed design.

1 Claim, 6 Drawing Sheets
